SILENCER

Floyd E. Deremer, Detroit, Mich.

Application April 7, 1937, Serial No. 135,600

1 Claim. (Cl. 181—62)

This application relates to silencers and particularly to silencers for exhaust gases of automobile engines.

One of the important problems in connection with the design and development of silencers is the problem of minimizing shell noises, which are noises produced by vibration of the outer shell of the silencer, such vibrations being produced by the impinging of sound waves against the shell. 5 Various expedients have been adopted for the purposes of minimizing shell noises. One such expedient is the padding of the shell with asbestos padding or the like; another is the reinforcing of the shell by the provision of transverse 10 supporting and bracing diaphragms. In this application I disclose an arrangement which has not only proven successful, insofar as minimizing shell noises is concerned, but has also proven more satisfactory than presently known expedients for the reason that it is an arrangement which is 15 inexpensive to adopt and to utilize.

Briefly, it may be stated that my arrangement comprises the use of a multiply shell, with pressed-out spots provided in either one of the plies to engage the other and thus space the plies relatively and form an annular air space between them. 20

For an understanding of my arrangement reference should be had to the appended drawing showing a silencer provided with my arrangement. 25 In this drawing,

Fig. 1 is a fragmentary sectional view of a silencer, with parts improperly proportioned for purposes of exaggeration in an effort to enhance the clarity of the disclosure; 30

Fig. 2 is a transverse section on line 2—2 of Fig. 1;

Fig. 3 is a diagrammatic representation of a silencer as if provided with the construction of the invention. 40

Referring to Fig. 3 particularly, it will be seen that this figure shows a silencer of the through type having therein an inner tubular shell 11 and an outer tubular shell 12. It is understood that sound waves therefrom impinge against the outer shell, causing vibrations thereof which in turn produce shell noises. 45

For the purposes of reducing such vibrations and noises of the outer shell, the outer shell of the silencer herein disclosed is arranged in accordance with my invention. Consequently it is formed of two plies 12a and 12b and the inner plies is provided with pressed-out spots 14 which

extend radially outwardly of the inner plies into engagement with the inner surface of the outer plies.

The spots are formed as "dimples" spot-pressed out of the metal of the inner plies, and in a preferred embodiment substantially the entire area of the inner plies is provided with these substantially uniformly spaced dimples. 5

It is not believed at present that the proportions and spacing of the dimples is of importance in connection with the invention. However, in order that a clear understanding of my invention may be obtained, I describe an embodiment which has been made and tested and found satisfactory insofar as shell noises are concerned 10 and in which it appears that shell noises have been minimized greatly by the use of my invention. In this embodiment, the following dimensional characteristics existed; the shell was made approximately 6 inches in diameter and 17 inches 15 long; the shell outer plies was made of sheet steel of .018 inch thickness, the shell inner plies was made of sheet steel of .018 inch thickness; the dimples were spot-pressed outwardly to the extent of .020 inch in radial projection and the air 20 space between the inner and outer plies and between the spots was approximately .020 inch in thickness; the dimples were of .50 inch diameter and were spaced on 2.5 inch centers over the 25 entire area of the plies. 30

The spots, by spacing the plies relatively, insured the provision of a dead air space between the plies, and manifestly succeeded in minimizing shell noises to a tremendous extent. 35

While the use of two plies for a silencer shell is not now broadly new, since I disclosed this idea in an earlier application, Serial No. 62,043, filed February 3, 1936, I claim as now new the use of two plies and the provision of spots in one of them for the purposes described. 40

Now having described the silencer herein disclosed, reference should be had to the claim which follows for a determination of the invention.

I claim:

In a silencer of the class described, a multiply 45 sheet metal tubular shell inside of which are sound waves which impinge against the inner plies with the inner one of the plies having circular pressed out spots extending from it to the other to space the plies relatively and thus form an 50 annual air space between the plies.

FLOYD E. DEREMER.
